UNITED STATES PATENT OFFICE

JAMES FRANCIS KEY, OF PASADENA, CALIFORNIA, ASSIGNOR OF SIXTY-EIGHT PER CENT TO JAMES IRVINE, JR.

KNOCKDOWN STRUCTURAL TOY

Application filed July 30, 1930. Serial No. 471,717.

This invention relates to knockdown structural toys such as may be used by children for their own amusement. Such toys embody in their construction a plurality of structural units which can be readily put together to produce different articles such as trusses, bridges or other mechanical devices. The general object of this invention is to produce a combination of structural units of simple form which can be readily put together or separated for the purposes indicated above. More specifically, one of the objects of the invention is to produce structural units particularly adapted to form a bridge truss and truck carried on the same and cooperating with a crane which can also be constructed of the units.

A further object of the invention is to provide a joint member of simple construction particularly adapted for connecting structural bars together; also to provide such a joint with simple means for interlocking a bar and joint so as to prevent the accidental disengagement of the bar from the joint.

A further object of the invention is to provide a joint of simple form enabling bars to be readily connected together in different planes and out of alignment with each other, at the same time enabling the bars to assume different angular positions with respect to each other; also to provide a joint of this character with a construction enabling the plate forming the joint to lock the bars into the sleeves that form a part of the joint.

Further objects of the invention will appear hereinafter.

The invention consists of novel parts and combinations of parts to be described herein-after, all of which contribute to produce an efficient knockdown structural toy.

A preferred embodiment of the invention is described in the following specification, while the broad scope of the invention is pointed out in the appended claims.

In the drawings:

Figure 1 is a side elevation illustrating by way of example, a toy truss or bridge carrying a track and truck running on the track and cooperating with a crane.

Figure 2 is a plan of the track and truck illustrated in Figure 1.

Figure 3 is a side elevation and partial section broken away illustrating one of the vertical struts or columns of the truss, certain parts being broken away. This view is a section taken at one side of the truss on the line 3—3 of Figure 1.

Figure 4 is a vertical section taken on the line 4—4 of Figure 3, certain parts being broken away.

Figure 5 is a horizontal section taken about on the line 5—5 of Figure 1 and particularly illustrating details of the construction of the windlass.

Figure 6 is a section and partial elevation broken away and illustrating a type of joint enabling two rods to be connected together in different planes and out of alignment with each other in such a way as to enable the angular relation of the rods to be altered at will.

Figure 6a is a plan of one side of a plate used in the joint illustrated in Figure 6 broken away and particularly illustrating a type of sleeve which I prefer to employ in this type of joint.

Figure 7 is a section on line 7—7 of Figure 6 further illustrating the joint shown in Figure 6, certain parts being broken away or shown in section.

Figure 8 is a side elevation of a sleeve unit which may be employed for connecting two bars which are in longitudinal alignment with each other.

Figure 9 is a vertical section taken at one side of a truck and illustrating the elements employed in mounting an axle on the truck frame.

Figure 10 is a view similar to Figure 9 but illustrating an embodiment of the invention in which the axle is mounted on a joint unit of special construction and having a means for fastening the wheels of the truck on the outside of the joint.

Figure 11 is a vertical section taken on the axis of an axle and illustrating the construction in which the truck frame can be mounted directly on the axle supported on its upper side.

Figure 12 is a double view showing a side elevation and edge view of a tension rod which may be used as a diagonal brace in

the truss structure or in a similar situation.

Figure 13 is a cross-section taken on the line 13—13 of Figure 5 and further illustrating details of this joint.

5 Figure 14 is a double view showing a side elevation and edge view of an end fitting and also showing a short portion of a tie bar or rod of round type instead of the flat type shown in Figure 12.

10 Figure 15 is a perspective illustrating a joint particularly adapted for forming a truss.

15 Figure 16 is an end view of a tubular rod to cooperate with this joint and particularly illustrating interlocking means for securing a tubular rod to a joint having an arm of the type illustrated in Figure 15.

20 Referring more particularly to the parts and especially to Figures 1 and 2, 1 indicates a bridge structure as an example of a structure that could be produced by employing my novel structural elements and 2 indicates a truck capable of being constructed in like manner and running on a track 3 on the lower members of the bridge or truss 1. The track 3 extends beyond the end of the bridge so as to enable the truck to cooperate with a crane 4 having a windlass 5 to enable the child to remove a load from the truck.

25 30 If desired, the truck may be attached to an endless cord 6 passing around guide pulleys 7, 8 and 9 and carrying a handle 10 fixed to it which can be moved to and fro by the child's hand to cause the truck to travel to and fro on the track.

35 In Figures 3 and 4 and also 15 I illustrate structural elements used in the assembly of the truss 1. These parts include a joint 11 which is particularly useful at the upper part of the truss. This joint includes two arms 12 integrally connected by a bend 13 and provided with a cross bar 14 rigidly secured at its middle point to the bars 12 in the angle between them and at their junction with each other. At this point 15 the bar 14 is preferably connected to the angle member composed of the arms 12, by welding or soldering.

40 One of the arms 12 is employed for connecting a transverse strut member 16 which is preferably in the form of a split tube which fits closely at its end over the arm or shank 12. The tube and the arm are preferably provided with means for interlocking them by relative rotation. For this purpose the arm 12 is provided with a tapered tip 17 adjacent to which the arm is provided with a circumferential groove 18. The adjacent end of the tube is provided with two oppositely disposed inwardly projecting lugs 19 struck from the material of the tube (see Figure 16). The wedge shape tip 17 enables the arm to be inserted far enough to bring the groove 18 into alignment with the dogs 19 whereupon a slight rotation will engage the dogs in the

groove and lock the tube against longitudinal displacement from the arm.

45 The bar 14 is similarly formed with wedge shape tips 20 which cooperate with similar lugs 21 on the ends of horizontal tubular members 22 which are connected together in alignment and form the upper stringer of the truss.

50 The vertical struts or columns 23 of the truss are similar in form to the horizontal members 22 and interlock with the vertical arm 12 of the joint, as indicated in Figure 1. At the bends 13 of the joint 11 I prefer to provide small outwardly projecting integral lugs (see Figure 15) for a purpose which will 55 appear hereinafter.

55 At the base of each column 23 I employ a joint 25 comprising two arms 26 which are similar in construction to the arms 12 but at this point of the structure I may omit the horizontal bar 14 as this part of the truss is subjected to tension and furthermore, it is considerably reinforced by the presence of the track 3.

60 However, the legs 26 are connected by an integral bend 27 and this bend is provided with lugs 28. These lugs are useful (as indicated in Figure 3) for holding in place diagonal tension members 29 which may be of wire or of the form illustrated in Figures 35

12 and 14. The eyes 30 of these tension members are stopped by the adjacent lugs 28 from slipping around the bend 27 and lie between this lug and the adjacent end of a tubular, horizontal cross bar 31 which extends across at the floor of the truss and carries the track 3, said track comprising two rails 3a that are of round form and extend longitudinally, resting on top of the cross bars 31. Any suitable means may be employed for securing the rails 3a to the cross bars. In Figure 3, I illustrate a bracket 32 for this purpose, comprising a vertical plate having an opening 33 through it to fit over the cross bar and having an integral sleeve 34 open on its under side. This plate is made of light resilient sheet metal so that the sleeve can snap over the upper side of the rail 3a before the bracket 32 is slipped over the end of the cross bar 31.

65 The metal composing the bracket 32 is so thin that the presence of the sleeve 34 does not interfere with the movement of the truck wheels along the rails.

70 The crane includes a vertical post 35 which at the lower end supports the boom 36 of the crane. This post 35 must be held in upright position and this is accomplished by employing diagonal braces 37 and 38, and I provide a special joint for connecting these diagonals to the upper end of the post 35. This construction includes two brackets 39 and 40 comprising two superposed plates connected to the upper end of the post by a center pin 41 passing down through aligning openings 120

in the plates; this pin fits into the upper end of the tubular post 35. The plates 39 and 40 are provided with integral sleeves 42 at their edges and these sleeves receive lateral shanks 43, respectively, formed on the ends of the diagonal braces 37 and 38. The body of the diagonal brace 37 is of tubular type, its upper end receiving a shank or arm 44 that projects at right angles to the arm 43. 5 If desired, such a diagonal brace can be made of a solid bar 38, as illustrated in Figure 1, the upper end of which is provided with a sleeve 45, the upper end of which connects to an arm 46 similar to the arm 44. At the 10 lower end of the post 35 the same type of joint is employed (see Figure 5).

This elemental joint is illustrated in Figures 6 and 6a, although in Figure 6 the brackets are represented in a slightly different position with the sleeves located on opposite sides of a supporting post 47.

I shall now describe this elemental joint illustrated in Figure 6. This joint comprises two brackets 48 and 49, the body of each bracket being formed of a plate and each plate having an integral roll at its edge forming a sleeve 50. Each of these sleeves has a gap 51 so that it constitutes a split sleeve. In order to increase the gripping 20 force of this sleeve on a shank or pin thrust into it, I prefer to form the metal of the middle of the sleeve with an inwardly pressed 25 waist 52 of reduced internal diameter. With this construction of the sleeve it will 30 be evident that a shank 53 can be readily introduced into the enlarged mouth of the sleeve at the end, but will become tight when the pin or shank 53 reaches the middle of the sleeve. If desired, the shank 53 can be covered 35 with an inner metal split sleeve 54, so that it would enable the shank to have a good bearing in case it is necessary to rotate the member carrying the shank on the axis of the shank. The bracket plate may be 40 provided with a similar sleeve construction 45 to that just described.

In order to enable these brackets to maintain any angular position with respect to each other, one of the edges of one of the 50 plates may be crimped toward the opposite plate and one of the plates may be formed with an integral eyelet 56 which pivotally connects the plates together but enables them to be shifted on the axis of their connecting 55 pin 57. The crimped edge, of course, resists this movement frictionally.

Figure 7 is a section through a joint of the type illustrated in Figure 6 and illustrates that, if desired, the effect of a crimped edge 60 may be obtained by providing one of the plates with two crimped edges 58 forming an angle with each other.

In Figure 8 I illustrate a sleeve element 59 for connecting two adjacent ends of two rods 60, said sleeve being split and having its mid-

dle portion offset inwardly, as indicated at 61, to form a constricted clamping point in the sleeve into which the ends of the rods 60 can be forced so as to be clamped friction-tight. 70

My plate form bracket elements carrying a pivot hole and a sleeve are useful for constructing the truck frame as illustrated in Figure 9, in which figure 62 illustrates one of the tubular axles of the truck. The truck 75 wheel 63 is mounted on a pin 64 thrust friction-tight into the end of the split tube 62 and the outer end of the pin is provided with a head 65 that seats against the outer side of a vertical, plate-form bracket 66, the lower 80 end of said bracket plate having an integral sleeve 67 to clamp over horizontal split tube 68 that forms a longitudinal side frame bar of the truck. (See Figure 2.) The ends of these bars 68 are connected by suitable cross 85 bars 70 constructed with corner angles 71 having legs received in the open ends of the tubular bars.

A bracket plate of the general type described above may be used in a way to enable rods to be inserted in the sleeves by a lateral movement and then locked in the sleeves by a slight rotation of the brackets. This is accomplished by having the plates of angular form so that when rotated, the corner 73 95 will project across the sleeve (see Figure 5 in connection with Figure 13). In this type of construction just referred to the sleeve 74 is open on the side toward the opposite bracket plate (see Figure 13). 100

These swivel bracket plates of this type are also useful in a construction such as that illustrated in Figure 11 for attaching a truck frame to an axle. In this view 75 indicates the upper plate having an integral sleeve 76 at one edge and 77 indicates the lower plate having a sleeve 78 at an edge extending substantially at right angles to the axis of the sleeve 76 and below the same. This sleeve 78 receives a tubular axle 79 carrying a wheel 80 of the truck attached as illustrated in Figure 9. The plates 75 and 76 are connected by a vertical swivel 81. The sleeve 76 carries a longitudinal bar 82 corresponding to the longitudinal bar 68 of the truck as illustrated in Figure 2. 105 110 115

The joint element illustrated in Figure 15 is useful in constructing a wagon or a truck having a super-structure above the axle. This is illustrated in Figure 10, in which 82a 120 indicates a joint having a vertical arm 83 and a horizontal arm 84, in the angle of which a bar 85 is rigidly secured, the inner end of said bar being received in the end of a tubular axle 86 and the outer end carrying a 125 wheel 87.

This wheel may be held on the axle by means of a coil spring 88, the coils of which yieldingly clutch the side face of the bar. One end of this coil may be provided with a 129

substantially lateral extension 89. In putting this keeper coil 88 in position it may be rotated by the handle 89 in a direction tending to uncoil the coil. This will enable the coil to go on the bar in a substantially loose manner but as soon as the handle is released the coil will clasp the bar.

The swivel bracket unit is also very useful in constructing a tripod of the type illustrated in Figure 17. In this view 90 indicates a bottom bracket plate having an integral sleeve 91 at one edge and connected by a swivel pin 92 to an intermediate bracket plate 93 having an integral sleeve 94 at an edge. The two sleeves 91 and 94 are disposed at an angle to each other and receive laterally projecting shanks 95 integral with legs 96 that rest upon the ground. Above the intermediate bracket 93 the bracket plate 97 is provided, constructed in a similar manner and mounted on the swivel 92, being held above the intermediate bracket 93 by a distance sleeve 98. This upper bracket 97 has an integral sleeve 99 at one end receiving a shank 100 projecting laterally from the third leg 101 of the tripod.

If the tripod is to support a superstructure, this may be accomplished by employing one of my swivel brackets, as indicated at 102, embodying a plate 103 with an integral sleeve 104 at a vertical edge seated on the pin 92 and having a back plate with an integral sleeve 105 extending at right angles to the sleeve 104 and carrying a bar 106. The two bracket plates that form this swivel bracket are connected together on a horizontal pivot or swivel 107.

In Figure 5 I illustrate the preferred construction for mounting the windlass drum 5. This drum is mounted on a horizontal threaded shaft 108, the threads of which receive a nut 109 that can clamp against the adjacent head 110 of the drum. This nut 109 has a handle 111 for rotating it. By tightening up on the nut 109 by means of the handle 111 the drum can be held more or less friction-tight between the nut and the head 112 on the outer end of the drum shaft. This will enable the child to give a yielding resistance to the rotation of the drum in using the cord or cable 113 that is supported by the boom and provided with a hook 114 for handling a load such as illustrated on the truck in Figure 1.

It is understood that the embodiment of the invention described herein is only one of the many embodiments this invention may take, and I do not wish to be limited in the practice of the invention, nor in the claims, to the particular embodiment set forth.

I claim:

1. In a knockdown structural toy, a joint having a pair of superposed plates pivoted together on an axis at right angles to the plane of the plates, each of said plates hav-

ing an integral sleeve formed at an edge thereof to receive a structural rod, and a tubular rod attached to said plates coaxial with their pivotal connection, one of said plates having a crimped edge projecting toward and engaging the opposite plate for offering a yielding resistance to the rotation of the plates on their pivotal axis.

2. In a knockdown structural toy, a joint having a pair of superposed plates pivoted together on an axis at right angles to the plane of the plates, each of said plates having an integral sleeve formed at an edge thereof to receive a structural rod, said plates being angular in form, and said sleeves being offset away from the plane of the plates and having an open side toward the plane of the plates to enable a rod to be inserted in each sleeve by a lateral movement, said plates operating when rotated on the pivotal axis, to project over the open side of the sleeve and lock the rods in them.

3. In a knockdown structural toy, a joint consisting of a pair of superposed pivoted plates, each plate having an integral split sleeve formed at one edge thereof, a structural rod having a shank with a tapered tip fitting into said sleeve, and means on the pivotal axis of the plates for attaching a rod to the same to extend at right angles to the plane of the plates.

4. A joint for a knock-down structural toy having a pair of plates pivotally connected together, said plates being superposed and lying substantially in the same plane and each plate having an integral sleeve formed at its edge to receive a rod held between the sleeve and the opposite plate and pressed therebetween.

5. A joint for a knock-down structural toy having a plate with an integral sleeve formed at one edge of the plate, said sleeve being offset from the plane of the plate and open on the side toward the plane of the plate and capable of being snapped over a rod by a lateral movement of the plate and sleeve toward the rod.

6. A joint for a knock-down toy comprising a pair of superposed plates having a sleeve pivotally connecting the same and capable of receiving a central pin, said plates lying in a single plane at right angles to the axis of the sleeve and having integral sleeves formed at their edges to receive a rod corresponding to each sleeve.

Signed at Los Angeles, California this 3rd day of July, 1930.

JAMES FRANCIS KEY.
